The ornamental design for jewelry ring, as shown and described.

DESCRIPTION

FIG. 1 is a front, top perspective view of a jewelry ring showing my new design;

FIG. 2 is a rear, bottom perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken lines are provided to show the environment related to the claimed design, but form no part of the claim.
